UNITED STATES PATENT OFFICE.

WALTER CHIPPERFIELD, OF HORNCHURCH, ENGLAND, ASSIGNOR TO A. B. DICK COMPANY, OF CHICAGO, ILLINOIS, A CORPORATION OF ILLINOIS.

MANUALLY-OPERATED TYPE-COMPOSING MACHINE.

1,368,784.

Specification of Letters Patent. Patented Feb. 15, 1921.

Application filed April 27, 1920. Serial No. 377,047.

To all whom it may concern:

Be it known that I, WALTER CHIPPERFIELD, a subject of the King of Great Britain, residing at Kinkora, Great Nelmes, Hornchurch, Essex, England, have invented certain new and useful Improvements in Manually-Operated Type-Composing Machines, of which the following is a specification.

My invention relates to manually operated type composing machines of the character in which a detachable composing stick is moved successively into alignment with various type troughs and a single type is released from each of said troughs and permitted to pass into the composing stick. In my application Serial No. 354358, Type composing machines, filed January 27, 1920, I have described a type composing machine in which a series of type troughs are fixed adjacent to each other around the periphery of a stationary cylinder or cone, so that the type troughs were vertical or slightly inclined to the vertical. Each type trough contained a store of type letters which were free to slide down the troughs, the lower end of each trough having a mechanically operated retaining device through the medium of which the lowermost type in any trough could be released and permitted to pass into the composing stick which would at that time be located beneath that particular trough.

My present invention relates particularly to improvements in the construction and mounting of the type troughs in a machine of the character referred to, whereby the various parts may be held in the required position in a simple and effective manner and the assemblage of the parts may be easily and quickly carried out.

I accomplish this purpose by providing a supporting frame which includes upper and lower annular portions having radial slots in their inner surfaces. The type troughs are formed of a number of metal strips of T-section, the stems of the T-section members being inserted in the radial slots referred to, so that the heads or flanged portions of the T-section members will be in alignment with each other around the periphery of a cone or cylinder. The flanges or heads of these members are closely adjacent to each other, so that grooved type may pass and be held between the adjacent edges

of each pair of T-section members. The T-section members having been placed and secured in position, a conical or cylindrical structure is placed within the ring of conically or cylindrically arranged T-section members to support the same in position, and also to carry the type retaining and releasing mechanism and to provide a bearing for the upper end of the vertically arranged shaft from which the composing stick is supported.

In order that a clearer understanding of my invention may be had, attention is hereby directed to the accompanying drawings forming a part of this application and illustrating one embodiment of my invention. In the drawings Figure 1 represents a manually operated type composing machine embodying my invention partly in side elevation and partly in vertical section; Fig. 2 is a horizontal section taken on line 2—2 of Fig. 1; Fig. 3 is a detailed plan view of a portion of one of the annular plates provided for holding the T-section members forming the type troughs, some of said T-section members being shown in section mounted in position; Fig. 4 is an enlarged side elevation of one of the T-section members, together with supporting means therefor shown in section; and Fig. 5 is a similar view showing a modified form of construction.

Referring to the drawings, vertical pillars or standards 1 extending upwardly from the base plate 1^a of the machine are concentrically arranged at suitable distances apart. These standards 1 carry or are formed with two horizontal rings located one above the other, the lower ring 2 being of smaller diameter than the upper ring 3 when the type troughs are to be arranged around the periphery of a conical form, this being the construction which will be particularly described herein.

Each ring carries a flat horizontal annulus 4, preferably formed of sheet metal and extending inwardly from the ring. Each plate annulus 4 is provided with a series of radial slots 5 extending for a distance from its inner periphery and at suitable equally spaced distances apart. Preferably, holes 6 are pierced through each plate 4 in radial alignment with the slots 5 and at short distances outwardly from the same.

The type troughs are formed by a number of metal strips 7 of T-section which are to be mounted in position with the stems 7^a of the T-section members inserted in the radial slots 5. The outer edge of the stem of each T-section member is inserted in the vertically alined slots 5 of the upper and lower annular plates 4, the heads or flanges 7^b of the T-section members then being in alinement 5 with each other at short distances apart. With this arrangement a type letter indicated in dotted lines in Fig. 3 at x, formed with grooves in its stem may be passed and be held between the adjacent 10 edges of the heads of two T-section members.

The members 7 are preferably themselves formed with slots 8 in their outer edges, and within each slot is a tongue 9 which will 20 enter one of the holes 6 in each annulus 4 when the T-section members 7 are placed in position.

The tongues 9 within the slots 8 in each T-section member 7 may both depend from 25 the upper edge of the slot 8, as is indicated in Fig. 5, in which case the members 7 may be dropped into position within the slots 5 of the upper and lower annulus; or, if preferred, the said tongues may be oppositely arranged, as is shown in Fig. 4, in which case the members 7 are placed in position in the slots 5 of each annulus 4, and each annulus is then fixed to its carrying ring 2 or 3 and the members 7 are securely held in 35 position.

The T-section members having thus been placed so that they are carried both by the upper annulus and the lower annulus, a conical structure 10, such as a casting, having external projections 11 formed upon it, is placed within the interior of the conically arranged T-section members, the projections bearing against the interior surfaces of the heads of the T-section members, and, therefore, firmly holding the latter in position. If preferred, the projections 11 may take the form of annular ribs, slots if necessary being formed in the ribs so that the sliding of the heads of the type in the troughs thus 45 constituted is not interfered with.

The conical internal structure 10 serves to carry the annular series of type retaining and releasing levers located around the interior of the conically arranged troughs, such levers being indicated at 27 and 31, and also provides a bearing for the upper end of 55 a vertical axially arranged shaft 12.

In the type composing machine to which this invention particularly relates, as is disclosed in my prior application Serial No. 354358, the composing stick 32 carried from the vertical shaft 12 is brought to position successively beneath selected type carrying troughs of the font and the lowermost types 65 therein are released, so that they may pass

from the type troughs to the composing stick. Mechanism for positioning the composing stick and releasing the type in the troughs to fall therein is not included in the present invention and will, therefore, not be particularly described. The particular mechanism illustrated in the drawings herein corresponds with that described in my application Serial No. 377,046, filed on even date herewith.

What I claim is:—

1. In type composing machines, the combination of a supporting frame, horizontal annular plates carried thereby, one above the other, said plates having equally-spaced radial slots in their inner edges, a series of T-section members the stems of which are received within said slots, the flanges of said members being in alinement and closely adjacent, so that the adjacent flanges of each pair of members will form a type trough, and a frame within the interior of the T-section members, positioned to bear against the inner surfaces of the flanges of said members.

2. In type composing machines, the combination of a supporting frame, horizontal annular plates carried thereby, one above the other, said plates having equally-spaced radial slots in their inner edges, and openings short distances radially outward from said slots, and a series of T-section members the stems of which are received within said slots, the stems of said members having tongues formed adjacent their outer edges, adapted to enter said openings to hold said T-section members in position, said members having flanges which are in alinement and closely adjacent, so that the adjacent flanges of each pair of members will form a type trough.

3. In type composing machines, the combination of a supporting frame, horizontal annular plates carried thereby, one above the other, said plates having equally-spaced radial slots in their inner edges, and openings short distances radially outward from said slots, and a series of T-section members the stems of which are received within said slots, the stems of said members having slots formed in their outer edges and tongues formed within said slots, adapted to enter said openings to hold said T-section members in position, said members having flanges which are in alinement and closely adjacent, so that the adjacent flanges of each pair of members will form a type trough.

4. In type composing machines, the combination of a supporting frame, horizontal annular plates carried thereby, one above the other, said plates having equally-spaced radial slots in their inner edges, a series of T-section members the stems of which are received within said slots, the flanges of said members being in alinement and closely ad-

5 jacent, so that the adjacent flanges of each pair of members will form a type trough, and a frame within the interior of the T-section members, said frame having a side part of annular horizontal cross section, with lugs thereon positioned to bear against the inner surfaces of the flanges of said mem-

bers, and having a transverse part adapted to provide a bearing for the upper end of a vertical shaft.

10 This specification signed and witnessed this 12th day of April, 1920.

WALTER CHIPPERFIELD.
